DESIGN FOR A HOLDER OF CANDLES, MINIATURE FLOWER POTS OR SIMILAR ARTICLES

Judson Craig Eubank, New York, N. Y.

Application October 24, 1944, Serial No. 115,951

Term of patent 7 years

(Cl. D48—2)

To all whom it may concern:

Be it known that I, Judson Craig Eubank, a citizen of the United States, residing at New York, in the county of New York and State of New York, have invented a new, original, and ornamental Design for a Holder of Candles, Miniature Flower Pots or Similar Articles, of which the following is a specification, reference being had to the accompanying drawing, forming part thereof:

Fig. 1 is a frontal perspective view of a holder of candles, miniature flower pots, or similar articles, and

Fig. 2 is a side elevational view thereof, showing my new design.

I claim:

The ornamental design for a holder of candles, miniature flower pots or similar articles, substantially as shown.

JUDSON CRAIG EUBANK.
